UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

AUTOMATIC TRAIN-CONTROL SYSTEM.

Original application filed October 25, 1923, Serial No. 670,701, now Patent No. 1,620,188, dated March 8, 1927. Divided and this application filed November 26, 1926. Serial No. 150,901.

This invention relates to automatic train control systems, and more particularly to systems of the intermittent inductive type.

The present application is a division of my application, Serial No. 670,701, filed October 25, 1923, now Patent 1,620,188, March 8, 1927, for train control.

In providing apparatus for automatically controlling a train in accordance with traffic conditions ahead, it is desirable to be able to automatically restrict the speed of a train in a caution block if the train is to be brought to a predetermined low speed or to a stop before reaching the end of such a block, and to enforce a low limiting speed throughout the following or danger block providing traffic conditions have not cleared up in the meantime. On account of the speed at which the train may be running, weather conditions, the collection of ice and snow, and for various other reasons, it is found difficult to transmit control influences by physical contact between vehicle carried devices and cooperating devices located along the trackway. In providing means for transmitting control influences which are intended to restrict the movement of the train it is highly important that such influences be invariably transmitted under danger traffic conditions ahead, regardless of the speed of the train; whereas the transmission of restoring control influences need not necessarily be effective at all speeds, because the failure to receive a restoring or resetting influence merely causes the movement of the train to be unnecessarily restricted and therefore is on the side of safety.

With the above and other considerations in mind the principal object and purpose of the present invention contemplates the provision of means to transmit restrictive control influences from the trackway to a moving vehicle inductively by the employment of alternating current and effective at all speeds and which means is constructed on the normally closed circuit principle so that the failure of a circuit will cause the transmission of a control influence and restrict the movement of the train regardless of traffic conditions ahead, and to provide means for transmitting a restoring influence which is dependent on a source of direct current energy and possibly is effective only for speeds above a predetermined low speed and

which is constructed entirely on the open circuit principle so that the failure of a circuit prevents the transmission of a restoring control influence, thereby also functioning on the side of safety.

More specifically it is proposed to provide an inert trackway device which is adapted to reduce the reluctance of a magnetic circuit including a car-carried core upon passage of the car-carried core by said trackway device under predetermined traffic conditions ahead, whereby flux is diverted from leakage paths and caused to pass instead through a secondary coil thus causing a higher opposing voltage in the circuit and causing de-energization of a relay.

Other objects, purposes, and characteristic features of the invention will appear as the description thereof progresses.

In describing the invention in detail reference will be made to the accompanying drawings in which:—

Fig. 1, illustrates conventionally one arrangement of trackway circuits and devices embodying the present invention; and

Fig. 2 shows, diagrammatically, cooperating car-carried apparatus in which the various devices have been shown conventionally.

Track equipment.

Referring to Fig. 1 of the drawings, there has been shown a trackway of the usual construction including the rails 1 which are divided by insulating joints 2 into blocks in the usual manner, the block I and the adjacent ends of two other blocks H and J having been shown; since the various blocks are the same like parts thereof have been given the same reference characters with distinctive exponents. Each of the blocks is provided with the usual trackway battery 3 at the exit end thereof and a track relay 4 at the entrance end, the direction of traffic being from left to right as indicated by the arrow. At the entrance end of each block is preferably provided a way-side signal of the usual type; although these signals may be of the color light, position light or semaphore type, for convenience semphore signals Z have been shown conventionally without illustrating their well-known control devices and circuits, these devices and circuits being well-known by those skilled in this particu-

lar art. In addition to the track relay 4 at the entrance to each block there is provided a line relay 5, which is under normally clear traffic conditions energized by a circuit including the front contact 6 of its associated track relay and the front contact 7¹ of the track relay of the block next in advance, so that the line relay 5 is energized, providing both the corresponding block and the block next in advance are unoccupied. This circuit receives its energy from a suitable source, such as a battery having terminals one of which has been designated B, the other terminal being connected to a common return wire C. This source of energy may comprise any number of batteries as for instance one for each block or may consist of a transmission line for supplying a series of blocks.

On the right hand side of the trackway and just before the entrance to each block is provided a knock-down element KD, comprising a magnetizable core 8 of general U-shape terminating in enlarged pole pieces 9 having a coil 10 on the back yoke thereof, which is normally maintained in a closed circuit of low resistance by the front contact 11 of the line relay 5.

In series with the track circuit of the block in the rear, that is, in series with the track battery 3 is connected a relay DL which for convenience may be called a series relay. This relay DL is designed so that its front contact 12 is, under clear traffic conditions, in the lower or de-energized position. If, however, a train occupies the track circuit including this relay DL sufficient current is caused to flow in the track circuit in question to effectively energize this relay DL and close its front contact 12. If desired this relay may be designed so that it will not assume its energized condition until a train very closely approaches the exit end of the block, it being understood that the track circuit current gradually increases as the train approaches the track battery 3.

On the left side of the trackway is provided a similar track element RS conveniently called the restoring or resetting track element, which comprises a core 15 of general U-shape terminating in enlarged pole pieces 16 and having a coil 17 on the back yoke thereof. As is obvious from the circuit shown in Fig. 1 of the drawing this coil 17 is energized by current derived from the battery 18, or other suitable source of energy, providing the block at the entrance to which the element RS is located is unoccupied and the series relay DL is in the energized condition, but is closed in a circuit of low resistance when said block is occupied and the series relay DL is in its energized condition, for reasons more clearly pointed out in connection with the operation of the system. In other words, the knock-down element KD

has its coil closed in a circuit of low resistance under clear traffic conditions in the block at the entrance to which it is placed, but has its coil open under caution and danger conditions of such block, whereas the restoring or resetting element RS has its coil closed in a circuit of low resistance under danger traffic conditions in the block at the entrance to which it is placed but has its coil energized by a source of electrical energy under clear and caution conditions of said block providing the series relay DL is in its energized condition.

Car-carried devices.

Referring to Fig. 2 of the drawing there has been conventionally illustrated a railway vehicle by the axles 25 and 26 and associated car wheels 27 and 28.

On the right side of the vehicle illustrated, assuming it to be moving in the direction as indicated by the arrow in Fig. 1, is provided a car element L comprising a core 50 of general inverted U-shape having depending legs terminating in enlarged pole pieces 51. On the rearwardly disposed leg of the core 50 is a primary coil P, which is normally energized by alternating current, (from a source not shown) and a secondary coil S in which voltage is induced by well-known transformer action. On the other leg of the core 50 is provided a secondary bucking coil SB, which is connected in series with the secondary coil S so that the voltage induced therein is opposite to the voltage induced in the secondary coil S. This car element L is suitably mounted on the truck of a railway vehicle, such as a tender truck, and is preferably supported by initially tensioned springs so that it is under ordinary conditions rigid with respect to the truck, but is adapted to move with respect thereto in cases of severe jars, and the like. This element is so supported that it magnetically cooperates with one or the other of the track elements KD or RS through an intervening air gap depending on whether the vehicle is moving pilot or tender first. On the left hand side of the vehicle is provided a similar car element L^a, which element L^a is identical in construction with the car element L and for convenience like parts have been given like reference characters with the distinctive exponent "a."

Operation.

Clear to caution.—In order to illustrate the operation of the system under various traffic conditions ahead, let us assume that the block J is occupied, or presents dangerous traffic conditions for some other reason, so that its track relay 4¹ is de-energized. Let us further assume that a train is equipped with suitable car-carried apparatus in its normal clear condition and is moving

in the block H in the normal direction of traffic. With the track relay 4¹ de-energized the circuit for the line relay 5 is broken thus de-energizing this line relay, thereby 5 putting the coil 10 of the track element KD in an open circuit. As the train approaches the signal Z, which is now indicating caution, the left hand car element first comes into communication with the resetting track 10 element RS. Since, however, the car-carried apparatus is in its normal condition the operation that takes place at this time need not be considered. After a further short 15 distance of movement of the train the right hand car element L comes into cooperating relation with the track element KD. While the car element L is disposed over the track element KD during its movement along the track the pole pieces 51 of the car element L 20 are momentarily bridged by the core of the track element KD, thereby reducing the reluctance of the magnetic circuit including the car-carried core 50. This decrease of the reluctance through the core 50 causes a 25 considerable increase in the alternating current magnetic flux passing through the coil SB. This increase of magnetic flux is due, to a large extent, it is believed, to diversion of flux from leakage paths. The total flux 30 through the primary coil is maintained substantially constant by reason of the law governing the flow of exciting current to transformers, and the like. Since the amount of flux passing through the coil SB 35 has been considerably increased by reason of the presence of the track element KD, and since, as just explained, the total flux passing the primary coil has not been materially changed, it becomes apparent that the voltage 40 induced in the coil SB is considerably larger whereas the voltage induced in the secondary coil S has been practically unchanged. Further, since the voltage induced 45 in the coil S is no longer capable of predominating over the voltage induced in the coil SB, at least not to an extent to maintain a suitable control stick relay (not shown) energized, such control relay momentarily assumes its de-energized position at the time 50 the car element L is in cooperating relation with the track element KD. This momentary de-energization of the control relay causes a front contact thereof to be opened. The opening of this front contact interrupts 55 the energizing circuit for the control relay permanently, so that the return of the conditions of the car element to normality will not again energize this control relay. With the control relay in its de-energized position 60 a contact (not shown) assumes its lower position and thereby de-energizes a train control device (not shown) and effects a restriction in the speed depending on the construction of this train control device. The 65 train may now proceed in block I in accord-

ance with the restriction enforced by the train control device thereby bringing the train to a low or minimum speed, or to a stop, by the time it reaches the end of the block I. For illustration of the various 70 parts, above and below referred to but described as "not shown", reference should be had to Patent 1,620,188 referred to above.

Caution to caution.—Let us assume that the train which formerly occupied the block J has advanced out of block J into the next block in advance so that the track relay 4¹ again assumes the energized position. As the train in question reaches a position in the block I at which the car element L^a 75 comes into communicating relationship with the resetting track element RS¹ a restoring control influence is transmitted. This restoring control influence is transmitted by reason of the car element L^a moving over 80 the track element RS¹ while this track element is energized by direct current. The passage of the car element L^a over the energized resetting track element RS¹ causes 85 a rapid building up and breaking down of magnetic flux linking the coils SB^a and P^a on the core 50^a, so as to cause a single cycle of voltage to be induced in the circuit including these coils, which is similar to a 90 single cycle of alternating electro-motive-force. The induction of this voltage in the coils just mentioned which are connected in series so that their voltages are cumulative, causes a current to flow which results in removal of the restricting control on the train. 95

Since the train ahead is still in the block next in advance of the block J, as heretofore assumed, the line relay 5¹ is in its de-energized position thereby putting the track element KD¹ in its abnormal active condition. As the train proceeds a little further, its passage by the element KD¹ causes the train carried control relay to respond the same as it did when the train entered the block I, thereby again putting the speed restricting device in its active condition the same as when the train in question moved from a clear into a caution block. 100

Caution to danger.—Had the train which formerly occupied the block J still been in this block J the front contact 13¹ of the track relay 4¹ would have assumed its lower position thereby completing a circuit of low resistance for the coil 17¹ of the restoring track element RS¹ as soon as the series relay DL¹ became energized, it being assumed that this relay DL¹ assumes its energized position when a train enters a block, such as the block I. With the coil of the restoring track element RS¹ closed in a de-energized circuit no voltage would have been induced in the coils SB^a and P^a of the car-carried element L^a, and consequently the train would have been restricted during its movement through the next block, namely 110 115 120 125 130

the block J; and if no restoring influence should be communicated at the end of the block J the restriction in the speed of the train would persist.

5 *Clear to clear.*—Let us now assume that the train is moving in the normal direction of traffic in the block H under clear traffic conditions of the blocks I and J, and with the car-carried apparatus in its normal clear 10 condition. As the train occupies the block H the series relay DL assumes its energized position by reason of the increased current flowing in the track circuit of the block H. The energization of this series relay DL, 15 bearing in mind that the track relay 4 is energized, causes the restoring track element RS to be energized. As the car element L^a passes over this track element RS there is no changing of the condition of the car-carried 20 apparatus. After a further short distance of movement the right hand car element L comes into communicating relation with the track element KD. Very little current changes, if any, take place in the upper 25 winding of the control relay during the passage of the car element L over the track element KD under this condition, that is, with the coil 10 of the track element KD closed in a circuit of low resistance. One 30 reason whereby this difference in the action of the car-carried apparatus may be accounted for when the car element L passes over a track element having its coil closed in a circuit of low resistance, is, that the 35 coil 10 of the track element acts as a bucking coil thereby preventing to a large extent the passage of flux through the yoke 8 of the track element KD, so that the reluctance of the car-carried core 50 is not materially 40 reduced although it is disposed directly over the core 8 of the track element KD. In other words, the presence of a coil closed in a circuit of low resistance surrounding the core 8 greatly resists and opposes the 45 passage of flux through this core, so that the flux passing through the bucking coil SB of the car element L is not materially different even though the car-carried element L is disposed directly over the track element KD 50 in its clear traffic condition.

55 *Disposition of track elements.*—The restoring track element RS is located along the track so that it will be encountered before the knock-down element KD is encountered so that when a train moves from one caution 60 block into a following caution block the speed restricting device may be restored to its energized condition and may then again be initiated when passing over the element KD located just beyond the element RS. This feature is specially desirable in systems in which the train control device is of a cyclic type. For instance, let us assume that a speed restricting device of the type shown 65 in the Simmon Patent 1,150,309 is employed.

While the train is passing through one block its speed will be gradually restricted so as to reach a predetermined low speed upon reaching the end of a caution block, and if the following block has assumed the caution 70 condition in the meantime the speed restricting apparatus is restored at the restoring track element RS and is again initiated at the knock-down track element KD, so that the speed restriction is removed upon entering the second caution block but the permissive speed is again gradually decreased while the train moves through this second caution 75 block.

In the particular circuit arrangement 80 shown the track element KD must be set back into the preceding block far enough so that the first axle of the train does not enter the block before the car element L has passed by the track element KD, because if this were possible the train would restrict itself by dropping the track relay and in turn the train control relay. If, however, it is desired to restrict the train only after it has passed a certain distance into a caution 85 block, this may be done by controlling the circuit for coil 10 on the track element KD by the track relay of the next block ahead, in the same manner as the line relay controls this coil in the circuit arrangement 90 shown.

Having thus shown and described one specific embodiment of the invention, it is desired to be understood that this has been done for illustrative purposes only, rather than for the purpose of showing the scope of the invention. It is also desired to be understood that various changes and modifications may be made to adapt the invention to the particular problems and systems encountered in practice, without departing from the nature, the scope or the idea or means underlying the present invention.

What is desired to be secured by Letters Patent of the United States is:—

1. Trackway apparatus for automatic train control systems comprising, a track electro-magnet for producing a magnetic field, a source of energy, a track circuit, a relay connected in series with said track circuit near the energy end of the track circuit, a circuit for energizing said electro-magnet including a front contact of said relay, the winding of said magnet, said source and suitable circuit controlling means governed in accordance with traffic conditions ahead, whereby said electro-magnet is only energized under predetermined traffic conditions ahead provided there is a train on said track circuit to increase the current in said relay.

2. Trackway apparatus for automatic train control systems comprising, tracks divided by insulated joints into blocks, a closed track circuit for each block including a track relay at the entrance end of the block

and a source of energy at the exit end, an electro-magnet for transmitting control influences to a moving vehicle on said track, a series relay at the exit end of each block connected in series with said track circuit and designed so that it assumes its de-energized position under normal conditions of the track circuit but assumes its energized position when the track circuit is occupied by a train, 10 and a circuit for energizing said electro-

magnet including a contact of said series relay closed when the series relay is energized and circuit controlling means governed in accordance with traffic conditions ahead.

15 3. Trackway apparatus for automatic train control systems comprising, a track element including a core of magnetizable material disposed along the trackway so as to be in communicating relationship with suitable 20 car-carried apparatus, a coil on said core, and means for energizing said coil under clear caution traffic conditions ahead and for connecting said coil in a closed circuit of low resistance under dangerous traffic conditions 25 ahead.

30 4. Trackway apparatus for automatic train control systems comprising, a track element including a core of magnetizable material disposed along the trackway so as to be 35 to be in communicating relationship with suitable car-carried apparatus, a coil on said core, and means for energizing said coil when the track directly ahead is unoccupied and the track directly in the rear of said element 40 is occupied, and for closing said coil in a circuit of low resistance when the track directly ahead and the track directly in the rear of said element is occupied.

45 5. Trackway apparatus for automatic train control systems comprising, a track element including a core of magnetizable material disposed along the trackway so as to be in communicating relationship with suitable car-carried apparatus, a coil on said core, and means for energizing said coil under clear traffic conditions ahead and for connecting said coil in a closed de-energized circuit under dangerous traffic conditions 50 ahead, providing there is a train approaching said element from the rear.

55 6. Trackway apparatus for transmitting control influences from the trackway to suitable car-carried influence receiving apparatus of train control systems comprising, a track divided into blocks by insulating joints, a track relay connected across the rails at the entrance of each block, a series relay and a source of energy connected in series and bridged across the rails at the 60 exit end of each block, said series relay only assuming its energized condition if there is a train in said block, an influence communicating device including a core having a coil thereon located near the entrance to a block, 65 a control circuit for energizing said coil in-

cluding a source of energy and a contact controlled automatically in accordance with traffic conditions in said block only, said control circuit also including a front contact of the series relay of the track circuit of the 70 next block in the rear, whereby said control circuit is closed only under predetermined traffic conditions of the first mentioned block provided there is a train in said next block in the rear.

75 7. Trackway apparatus for inductively transmitting control influences to suitable car-carried apparatus upon passage of trains thereby comprising, a core having projecting poles located so as to be traversable by a suitable car-carried influence receiving means, a coil on said core, means for closing an energizing circuit for said coil, at one point, only under unoccupied conditions of the block ahead of the control point at which said core is located, and a relay connected in series with the track battery of the block in the rear of said first mentioned block having a contact, which is closed when the relay is energized, at another point in said circuit, 80 said relay assuming its energized condition only if there is a train on the track circuit of said block in the rear, whereby said coil is only energized if there is a train approaching said control point and unoccupied conditions are existing in the first mentioned block.

85 8. Trackway apparatus for automatic train control systems comprising, a track element including a core of magnetizable material disposed along the trackway so as to be in communicating relationship with suitable car-carried apparatus, a coil on said core, and means for energizing said coil under clear traffic conditions ahead and for connecting said coil in an inert closed circuit of low 90 resistance under dangerous traffic conditions ahead, an inductor of magnetic material disposed along the trackway to be in communicating relationship with other car-carried apparatus, a coil on the inductor, and means for opening a circuit including the coil, under dangerous traffic conditions ahead.

95 100 9. Trackway apparatus for automatic train control systems comprising, a track element including a core of magnetizable material disposed along the trackway so as to be in communicating relationship with suitable car-carried apparatus, a coil on said core, and means for energizing said coil when the track directly ahead is unoccupied and the track directly in the rear of said element is occupied and for closing said coil in a circuit of low resistance when the track directly 110 ahead and the track directly in the rear of said element is occupied, an inductor of magnetic material disposed along the trackway to be in communicating relationship with other car-carried apparatus, a coil on the inductor, and means to open a circuit including the coil, under dangerous traffic conditions ahead.

including the coil, under dangerous traffic conditions ahead.

10. Trackway apparatus for automatic train control systems comprising, a track element including a core of magnetizable material disposed along the trackway so as to be in communicating relationship with suitable car-carried apparatus, a coil on said core, means for energizing said coil under clear traffic conditions ahead and for connecting said coil in a closed de-energized circuit under dangerous traffic conditions ahead, providing there is a train approaching said element from the rear, an inductor of magnetic material disposed along the trackway to be in communicating relationship with other car-carried apparatus, a coil on the inductor, and means to open a circuit including the coil, under dangerous traffic conditions ahead.

11. Trackway apparatus for inductively transmitting control influences to suitable-carried apparatus upon a passage of trains thereby comprising, a core having projecting poles located so as to be traversible by a suitable car-carried influence receiving means, a coil on said core, means for closing an energizing circuit for said coil at one point only under clear traffic conditions of the block ahead of the control point at which said core is located, a relay connected in series with the track battery of the block in the rear of said first mentioned block having a front contact at another point in said circuit, said relay assuming its energized condition only if there is a train on the track circuit of said block in the rear whereby said coil is only energized if there is a train approaching said control point and clear traffic conditions are existing in the first mentioned block, a magnetizable inductor on the trackway positioned to be traversed by car-carried apparatus, a coil on the inductor, and means to open a circuit including the coil, under dangerous traffic conditions ahead.

12. Trackway apparatus for automatic train control systems, comprising, a track element including a core of magnetizable material disposed along the trackway in communicating relationship with suitable car-carried apparatus, a coil on said core, and means for energizing said coil under both clear and caution traffic conditions ahead and for connecting said coil in a closed de-energized circuit under dangerous traffic conditions ahead, provided there is a train approaching said element from the rear.

13. Trackway apparatus for automatic train control systems, comprising, a track element including a core of magnetizable material positioned along the trackway for communicative relation with suitable car-carried apparatus, a coil on said core, means for energizing said coil under both clear and caution traffic conditions ahead and for connecting said coil in an inert closed circuit of low resistance under dangerous traffic conditions ahead, an inductor of magnetic material disposed along the trackway in communicative relation to other car-carried apparatus, a coil on the inductor, and means to open a circuit including the coil under both danger and caution traffic conditions ahead.

14. Trackway apparatus for automatic train control systems, comprising, a track divided into blocks, a track element including a core of magnetizable material disposed along the trackway at the entrance to one block so as to be in communication with car-carried apparatus, a coil on the core, and means for energizing said coil when said one block is unoccupied, and the block immediately to the rear thereof is occupied, and for closing said coil in a circuit of low resistance when said one block, and the block immediately to the rear thereof, are both occupied.

In testimony whereof I affix my signature.
CHARLES S. BUSHNELL.
